PROCESSING WELL FLUIDS

William B. Plummer, Chicago, Ill., assignor to
 Standard Oil Company, Chicago, Ill., a corpora-
 tion of Indiana

Application December 20, 1939, Serial No. 310,200

1 Claim. (Cl. 260—683.1)

This invention relates to methods of hydrocarbon conversion and recycle which are particularly applicable to use in connection with wells of the so-called distillate or condensate type although applicable also in connection with production from other types of wells when it is desired to cycle gases to repressure an underground formation.

Production from certain deep hydrocarbon reservoirs of the so-called distillate type is wholly or largely in the vapor phase although these vapors contain substantial amounts of normally liquid hydrocarbons commonly including gasoline hydrocarbons and hydrocarbons boiling somewhat above the gasoline range as well. The existence of these hydrocarbons in the vapor phase in the sub-surface reservoir is due to the high pressure existing in the formation which brings about a phenomenon known as retrograde vaporization whereby a hydrocarbon system which would give a liquid phase as well as a vapor phase at moderate pressures or even at atmospheric pressure exists as a single dense vapor phase in the reservoir. In handling production from such reservoirs the well fluids are reduced in pressure and sometimes cooled to bring about the phenomenon of retrograde condensation whereby a large part of the normally liquid hydrocarbons and also a substantial part of the three and four carbon atom hydrocarbons are thrown out in the liquid phase and separated. This liquid phase is then stabilized or flashed to atmospheric pressure and the gases originally separated as well as those resulting from the stabilization or flashing operation are recycled to the underground formation from which they were produced thereby maintaining the pressure in such formation and maintaining or enhancing the retrograde vaporization phenomenon therein, thus greatly improving the ultimate recovery from the reservoir. In some instances these gases are used for the maintenance of the pressure in, or the repressuring of, an underground formation other than that from which they originated.

It has also been proposed to recover the liquid components of high pressure well fluids, of the type described, by processes of high pressure absorption followed by recycling of the gases to the same or another sub-surface reservoir for pressure maintenance or repressuring purposes.

While the present invention is particularly applicable to production from high pressure wells of the distillate type, it is also applicable to ordinary gas wells (particularly where natural

gasoline is present in the gas) and to wells producing a liquid phase as well as a gas phase at the well head.

It is an object of the present invention to provide methods for enhancing the yield of motor fuel in connection with production from oil and gas wells and particularly in conjunction with production from wells of the distillate type. Another object of the invention is to accomplish 5 this increased production of motor fuel without seriously diminishing the amount of gas available for recycling to the sub-surface reservoir or for cycling to another sub-surface reservoir. A still further object of the invention is to provide 10 a method for increasing the yield of motor fuel in conjunction with producing operations of the type previously mentioned while simultaneously increasing the amount of gas available for recycling purposes.

Another object of my invention is to provide 20 in the connection previously described a gas of improved character for pressure maintenance or repressuring purposes.

It is also an object of the invention to accomplish 25 the foregoing objects with simple apparatus having a dual function. A further object of my invention is to accomplish the objects previously described in a particularly economic and expeditious manner.

Another feature and object of my invention is 30 the provision of a polymerization process in conjunction with a retrograde condensation or high pressure absorption operation in which the polymerization process and the retrograde condensation or high pressure absorption process are combined to accomplish results which cannot be accomplished by either alone. More particularly it is an object of my invention to combine a 35 retrograde condensation or high pressure absorption operation and a polymerization operation using in part the same equipment for both operations.

A further object of my invention is to provide 40 a new and improved absorption medium for use in high pressure absorption processes in connection with production from wells of the distillate type.

Other and more detailed objects, advantages 45 and uses of my invention will become apparent 50 as the description thereof proceeds.

The normal production from distillate wells includes a large amount of methane and progressively lower amounts of higher paraffinic hydrocarbons. Ordinarily this includes a substantial 55 amount of C₂, C₃ and C₄ hydrocarbons, a sub-

stantial amount of hydrocarbons boiling in the gasoline range, i. e., up to about 400° F., and usually a fair and varying amount of still heavier hydrocarbons. It is customary in conjunction with both the retrograde condensation and the high pressure absorption types of process for handling such production to recycle practically all of the hydrocarbons having one, two and three carbon atoms per molecule and a large part of the four carbon atom hydrocarbons to the underground formation. In spite of this the amount of gas available for recycling purposes is necessarily quite considerably less than that produced so that pressure maintenance is not ordinarily completely successful. This is due first to the fact that the desirable normally liquid hydrocarbons are recovered and are not available for recycling and also to the fact that the fuel necessary in whatever process is used and in particular the fuel necessary for the operation of compressors is normally taken from the gas produced and this further diminishes the supply of recycle gas. Any process for the utilization of any of the normally gaseous hydrocarbons produced by such distillate wells has therefore been looked at askance since it is still further and more seriously diminishes the supply of recycle material. However, the process of my invention utilizes certain of these lower hydrocarbons for the production of further amounts of hydrocarbons boiling in the motor fuel range without seriously diminishing the supply of gases available for recycling and in many instances it serves to increase the supply of such gases as well as improving their function in the underground retrograde vaporization phenomenon.

Briefly this is accomplished by the isolation of a fraction heavier than methane and lighter than gasoline, normally a C₃—C₄ fraction, subjecting this at high temperatures and preferably at high pressures to a thermal polymerization process which produces not only a large amount of gasoline range hydrocarbons but also an amount of gas of even greater volume than the gaseous volume of the hydrocarbons going to the polymerization operation. These gases are available for recycling and thus avoid the objection previously described. The thermal polymerization process involves amongst other reactions the dehydrogenation of C₃ and C₄ hydrocarbons and of ethane to some extent and the polymerization of the olefinic hydrocarbons thus produced to form normally liquid hydrocarbons which ordinarily boil largely in the gasoline range but include a heavy polymer fraction which is very useful in connection with a high pressure absorption operation.

If the dehydrogenation and polymerization reactions were the only ones involved, one molecule of hydrogen would be formed for each molecule of hydrocarbon consumed in the process. Thus the amount of gas available for recycle would not be diminished. Also the hydrogen is believed to have a substantially greater retrograde vaporization effect than do the hydrocarbons from which it was formed. However, the process is even more advantageous than this since other reactions are involved producing hydrocarbons lighter than those consumed. In particular these thermal polymerization processes are notable for the production of a very substantial amount of methane which is excellent for recycle purposes. In fact the substitution of methane for a heavier hydrocarbon such as propane or butane makes the gas, volume per volume, much more efficient in the retrograde vaporization phenomenon. This pro-

duction of methane in the polymerization operation is accompanied by the production of cyclic hydrocarbons, notably benzene and other aromatic hydrocarbons which are highly desirable in a motor fuel. At the same time heavier aromatic hydrocarbons boiling above the gasoline boiling range are produced and these are highly useful in a high pressure absorption operation since the high critical temperature of aromatic hydrocarbons permits the operation of the absorption step at a higher pressure than would otherwise be the case. Since any increase in the pressure of the high pressure absorption operation diminishes the most expensive step of the process; namely, that of recompressing the gases for recycling to the sub-surface reservoir, the improved utility of this high pressure absorption medium is apparent. Thus not only does the polymerization operation produce large volumes of hydrogen and methane which are highly useful for recycling purposes, but without diminishing the supply of gas available for recycling an improved motor fuel is obtained in greater yields than would otherwise be the case and an improved high pressure absorption medium is simultaneously produced.

While the preferred embodiment of my invention involves the production of well fluids, particularly from reservoirs of the distillate type, the recovery of a normally liquid fraction, the separate recovery of a fraction of normally gaseous hydrocarbons heavier than methane, the thermal polymerization of this latter fraction and the recycling of all or part of the gases produced in the thermal polymerization operation along with those directly separated from the well fluids to the underground formation or to another underground formation, my invention also includes subjecting a fraction of normally gaseous hydrocarbons heavier than methane to separate steps of dehydrogenation and polymerization, both of which steps may be catalytic and may be accomplished at various temperatures and pressures by the use of various catalytic processes known to the art. These catalytic processes commonly operate at low pressures.

My invention will be described further with particular reference to the accompanying drawings which show in Figures 1, 2 and 3 respectively three alternative flow diagrams illustrating my invention. These drawings form a part of this specification and in them like reference numerals indicate like or corresponding parts.

Turning first to Figure 1, a producing well 11 furnishes well fluids from a sub-surface reservoir 55 which is normally a deep high pressure reservoir of the distillate type. While only a single producing well is shown it will, of course, be apparent that the production from any number of such producing wells can be combined and that normally my process will operate on the combined production from a group of such producing wells. The well fluids pass through valve 12 (which may be fully open) and then through line 13 to one or the other of driers 14. These driers may contain any desired drying material, for instance calcium chloride. The particular drier used at any particular time is, of course, controlled by the operation of valves 15. Normally one drier is on stream and the other is being regenerated by passing hot gases therethrough by the use of valves 16. The purpose of the drying operation is to remove water which would otherwise form natural gas hydrates on reduction of the temperature and pressure, thereby interfering with the operation of the subsequent apparatus. How-

ever, if the temperature and pressure of the separation step are such that with the particular well fluid involved hydrate formation does not occur to a troublesome extent, the drying step can, of course, be omitted.

The well fluids, preferably dried, pass through cooler 17 and pressure reduction valve 18 to separator 19. The cooler and pressure reduction valve are controlled to give a temperature and pressure in the separator which may be varied within considerable limits depending on the desired operation and the particular character of the well fluids. However, they are such as to give a substantial recovery of liquid hydrocarbons by virtue of the retrograde condensation phenomenon. Normally the pressure in separator 19 will be between 600 pounds per square inch and 2,000 pounds per square inch and is chosen on an economic basis. In other words, the pressure should be as high as possible in order to reduce the cost of recompressing the gases but, on the other hand, the lower the pressure so long as it remains within the retrograde condensation range, the larger the amount of liquid phase separated. The lower limit of the retrograde condensation range varies with the composition of the particular well fluids involved and is in general higher when these well fluids are rich in heavy hydrocarbons than when they are poor in heavy hydrocarbons. In most cases the pressure in separator 19 should be between 900 pounds per square inch and 1,800 pounds per square inch, the higher pressures generally corresponding to well fluids rich in heavy components and the lower pressures to well fluids poor in such heavy components.

Generally speaking, the lower the temperature in separator 19, the better the recovery and here again we have an economic factor involving the cost of cooling and the cost of eliminating hydrate difficulties. The separator can be operated at temperatures from -25° F. to +125° F. but ordinarily is operated at temperatures ranging between 0° F. and 75° F.

The liquid phase formed in separator 19 includes not only a major part of the normally liquid hydrocarbons present in the well fluids but also includes substantial amounts of normally gaseous hydrocarbons, particularly C₃ and C₄ paraffinic hydrocarbons. The gas phase in this separator is predominantly methane but also includes ethane and minor amounts of heavier hydrocarbons. This gas phase passes through line 20 and compressors 21 and thence through line 22 and valve 23 to one or more input wells 24 through which it is recycled to the underground formation from which production was effected through well 11 or it may be cycled to a different sub-surface reservoir for pressure maintenance or repressuring purposes. As previously pointed out, these gases act on the sub-surface reservoir to improve the ultimate recovery therefrom.

Turning now to the liquid phase in separator 19, this is removed through valve 25 under the control of float 26 and passes via line 27 and one or the other of valves 28 into fractionator 29. This fractionator is preferably a bubble tower operating under fairly high pressure, such as 100 pounds per square inch to 600 pounds per square inch, for instance 400 pounds per square inch, preferably not less than 250 pounds per square inch. The operation of this fractionating column will be described in more detail at a later point. Suffice it to say for the present that

the liquid phase from separator 19 along with all or part of the hydrocarbons produced by the polymerization step are separated in it into a liquid phase which is withdrawn through valve

5 30 under the control of float 31 and then through cooler 32 to product storage tank 33 and a gaseous phase which is withdrawn from the top of the fractionator through line 34. The liquid product in tank 33 contains the gasoline produced by both the retrograde condensation step and the polymerization step. It will also normally contain some small amount of heavier hydrocarbons and in many instances some slight excess of light hydrocarbons so that re-running 10 and often stabilization are necessary in order to produce a finished motor fuel. Due to the presence of the polymer gasoline, such a finished fuel is of high antiknock value and high quality although further refining operations can be and 15 often will be applied to it.

The gases withdrawn from the top of fractionator 29 through line 34 include practically all the propane and lighter hydrocarbons present in the liquid phase from separator 19 as well as in the initial product from the polymerization step and also include a substantial part, often a major part, of the C₄ hydrocarbons produced in the two operations. This gas stream passes to separator 35 in which a liquid phase rich in C₃ and C₄ hydrocarbons is separated by virtue of the operation of partial condenser 36. These liquid hydrocarbons are removed from the separator by pump 37 and a portion of them may be and normally is recycled as reflux to 20 fractionator 29 by means of valve 38 and line 39. Since the hydrocarbons recycled to the fractionator largely return to separator 35, the liquid phase from this separator is ultimately cycled via valve 40, line 41, heat exchanger 42 and line 43 to polymerization furnace 44 for conversion into normally liquid hydrocarbons, particularly gasoline range hydrocarbons.

It will be understood that depending on the pressure and top temperature in fractionator 29 and on the amount of cooling effectuated by cooler 36, the liquid phase in separator 35 may be largely C₄ hydrocarbons or largely propane whichever is desired. Normally the predominant hydrocarbon is propane. It will also be apparent that if the pressure in fractionator 29 is high and the top temperature of this fractionator is low the bulk of the C₄ hydrocarbons along with a large part of the propane can be eliminated from fractionator 29 into product tank 33 instead of going to separator 35. In this case, which is normally not the preferred operation, the product in tank 33 will, of course, require stabilization and the liquid phase in separator 35 will be rich in ethane. Thus the hydrocarbons going to polymerizer 44 are rich in at least one normally gaseous paraffinic hydrocarbon heavier than methane.

Turning to the gas phase in separator 35 this is removed via line 45 and passes through valve 46 to compressors 47 by means of which its pressure is increased to about the same pressure as that of the off-gases from separator 19 and the gases from separator 35 then pass along with those from separator 19 to compressors 21 for reinjection through input well or wells 24.

When the conditions are such that the gases from separator 35 contain substantial amounts of polymerizable hydrocarbons, a portion of these gases can be sent to polymerizer 44 via one of

compressors 47, valve 48, lines 49 and 41, heat exchanger 42 and line 43.

It is also normally desirable to use a portion of the gases from separator 35 for fuel in polymerization furnace 44 and these can be taken through valve 50, lines 51 and 52 and valve 53 to burner 54. Gas tank 55 is floated on the line or can be used to accumulate a portion of the gases produced. The amount of gas thus used as fuel is much less than that produced in the polymerization step, the remainder being available for use underground for pressure maintenance or repressuring purposes.

Adverting now to polymerizer 44 in more detail, the hydrocarbons entering it are preheated by means of heat exchanges 42, if so desired, and then pass with any desired routing through the coils of the polymerization furnace. This polymerizer is preferably operated at a temperature of 950 to 1150° F., for instance 1025° F., and at a pressure of 100 to 3000 pounds per square inch, for instance 1500 pounds per square inch. It is preferred to operate the polymerizer at a high pressure, preferably at least 1,000 pounds per square inch, to minimize recompression costs. As previously indicated, other types of polymerization systems can be used, preferably high temperature thermal polymerization systems but also including thermal and catalytic systems in which the gases are first dehydrogenated and then polymerized in a separate operation. While the operation of the polymerization step involves dehydrogenation as well as polymerization, in the strict sense of the latter term, I refer to the combined reactions, whether occurring together or in separate steps as polymerization. This is in accordance with usage in the art.

As shown the initial product from the polymerizer 44 passes out through transfer line 56 and then through heat exchanger 42 where it serves to preheat the incoming gases. The polymerization products then pass to evaporator 57 from which a heavy polymer fraction boiling above the gasoline range is removed via valved line 58 which is under the control of float 59.

* The vapor phase material from evaporator 57 passes through line 60 into fractionator 29.

Since the polymerization products entering fractionator 29 are normally at a much higher temperature than that of the liquid phase from separator 19, the polymerization products are introduced into the fractionator at a low level and the liquids from the retrograde condensation step enter at a high level. Thus the latter serve to supply a dephlegmating or reflux effect and greatly reduce or even eliminate the necessity of supplying other reflux or dephlegmation to the fractionator. On the other hand, the hot polymerization products serve to supply at least a large part and usually all of the heat required at the bottom of this fractionator and eliminate or greatly reduce the amount of reboiler heat which must otherwise be supplied at the base of this fractionator. In other words, the fractionator 29 is not only used to accomplish a double function in connection with the fractionation of the retrograde condensation products and the polymerization products as well but the two streams are utilized in such manner as to make for a peculiarly efficient fractionation operation.

While the simple flow diagram and apparatus arrangement shown in Figure 1 is particularly advantageous in many respects, it is also advantageous in other instances to use more complicated flow diagrams. This is particularly true 75

where large production is available and where the character of the formation and production from it are such that the productivity of the producing well or wells declines only very slowly so that a high capital investment is justifiable to obtain increased efficiency. Figure 2 illustrates some of these possibilities and also illustrates a simple process alternative to that of Figure 1 utilizing only a portion of the apparatus shown in Figure 2.

Adverting now to Figure 2 in more detail the production from one or more producing wells 11 which are preferably of the distillate type passes through cooler 17 and pressure reduction valve 18 into vessel 19 which, if valves 61 and 62 are closed and no absorber oil is introduced, operates as a retrograde condensation separator similar to that shown in Figure 1. One difference, however, is that instead of drying the gases entering separator 19 as in Figure 1, Figure 2 shows the use of an antifreeze system as an alternative method of preventing natural gas hydrate trouble. A liquid or gaseous antifreeze material, for instance calcium chloride brine, can be circulated with the well fluids through pressure reduction valve 18 and this serves to prevent the formation of natural gas hydrates. In the case of a liquid antifreeze material this, of course, separates at the bottom of separator 19 and is withdrawn under the control of float 63, which floats at the interface between the brine and the hydrocarbons, through valve 64 to an antifreeze, regeneration, storage and recycling system 65 from which it goes back into the line either preceding or following cooler 17. As shown the regenerated antifreeze is returned via valved line 66 between cooler 17 and pressure reduction valve 18.

As in the case of Figure 1, the gases, chiefly methane, from separator 19 pass through line 20 and compressors 21 which are shown as controlled by the pressure in line 20 and thence through line 22 to one or more input wells 24.

Turning to the liquid hydrocarbons in separator 19, these are withdrawn through valve 25 under the control of float 26 and pass, by means of line 27, to surge drum 67. This surge drum can be operated at about the same pressure as separator 19 in which case it serves only as a surge drum or it may be operated at a pressure intermediate between that of separator 19 and that of stabilizer 29 in which case it serves not only as a surge drum but also as a separator. Thus, for instance, the retrograde condensation separator 19 can be operated at 1,200 pounds per square inch, the surge drum and separator 19 at 600 pounds per square inch and the stabilizer 29 at 300 pounds per square inch.

The liquid present in surge drum 67 passes through pressure reduction valve 68 into stabilizer 29. Before entering the stabilizer, all or part of it can be used, if so desired, to cool the stabilized product by wholly or partially closing valve 69 and opening valves 70, thereby passing this cooled stream from the surge drum through heat exchanger 71. On the other hand, it is often advantageous to utilize the low temperature of this material from the surge drum not as an indirect heat exchange material in heat exchanger 71 but rather as refluxing material. When the stream from the surge drum has not been passed through heat exchanger 71 prior to introduction into the stabilizer, the point of introduction is preferably the one corresponding to the upper of the three alternative valved lines 72.

In stabilizer 29 hydrocarbons lighter than

butane are removed and the stabilizer is preferably operated at such pressure, top temperature and reflux ratio as to eliminate such part of the C₄ hydrocarbons as are not desired in the finished motor fuel. Reflux in addition to that occasioned by the use of the cold material from surge drum 67 can, if desired, be furnished by passing the off-gases from the stabilizer through partial condenser 36 to separator 35 from which a part of the liquid phase can be pumped by means of pump 37 through valve 38 and line 39 back into the top of stabilizer 29. If the hot material from polymerizer 44 is introduced into stabilizer 29 through valve 73, as will hereinafter be discussed, little or no reboiling will be necessary. However, if this is not the case, i. e., if a separate fractionation apparatus is used for the polymerization products, reboiling can be furnished by means of trap-out plate 74 and heater 75. In fact some heating at this point may be desirable even if the hot polymerization products are discharged into the stabilizer.

Stabilized material from stabilizer 29 is cooled in heat exchanger 71 and/or cooler 32 and then passes to intermediate product storage tank 33. Since the material in this intermediate product storage tank normally contains a considerable amount of hydrocarbons boiling above the gasoline range, it may be rerun and is therefore withdrawn by means of pump 76 and passed through line 77 to rerun tower 78. When rerunning is carried on immediately cooler 32 may be bypassed by closing valve 32a and opening valve 32b.

Rerun tower 78 can be operated at low pressure and is a conventional piece of equipment. If cooler 32 has been used the material from intermediate product tank 33 can be used to cool the hot bottoms from rerun tower 78 by closing valves 79 and opening valves 80 thus passing this relatively cold stream through heat exchanger 81. In any event the material to be rerun enters the rerun tower which is provided with dephlegmating coil 82 and reboiling equipment 83 and stabilized gasoline of the desired end point is taken off through line 84, passed through condenser 85 and then passed via line 86 to storage tank 87 which contains the final gasoline produced directly from the distillate. This gasoline can be withdrawn through valved line 88 for shipment, chemical treatment or use. On the other hand, it can be passed through valved line 89 and line 90 and blended in line 91 with the gasoline produced in the polymerization operation and this is in general desirable since the polymer gasoline has a relatively high knock rating and the distillate gasoline has a relatively high volatility so that the two together make an excellent motor fuel.

The bottoms from the rerunning operation are cooled in heat exchanger 81 and/or cooler 92 and thence passed through valved line 93 to storage tank 94. Alternatively part of this heavy distillate can be passed through valved line 95 to tank 96 and blended with the heavy polymer which, as will hereinafter appear, is normally the main product passing to this tank. As a matter of fact, heavy distillate tank 94 can be dispensed with and all of this heavy distillate can be passed along with the heavy polymer to storage tank 96. However, this is not preferred particularly when vessel 19 is operated as a high pressure absorber rather than as a mere retrograde condensation separator since the heavy polymer is a better absorption medium than is the heavy distillate.

Returning now to separator 35 in connection with stabilizer 29, the liquids from this sepa-

rator are ultimately passed by pump 37 through valve 40, line 41 and heat exchangers 42 into the coils of polymerization furnace 44.

The gases from separator 35, on the other hand, can be utilized in a variety of ways which will depend for the most part upon their composition. This in turn depends on the pressures chosen for various parts of the apparatus and on the composition of the original well fluids. If 10 gases from surge drum 67 are not used as fuel, gases from separator 35 can be used as part or all of the fuel for polymerizer 44 in which case the necessary portion of these gases is passed through valve 97, line 98 and valve 53 to burner 54 of polymerizer 44. Fuel gas storage tank 55 normally floats on the line. On the other hand, the gases from separator 35 ordinarily contain some substantial amount of polymerizable constituents and it is therefore desirable to pass all 15 or part of them through valve 99, compressors 100, valve 101, lines 49 and 41, heat exchangers 42 and line 43 to the coils of polymerization furnace 44. The third possibility which is desirable when fuel gases are available from other sources and when, as is ordinarily the case, the 20 gases from separator 35 do not contain large amounts of polymerizable hydrocarbons is to pass all or part of these gases through valve 99, compressors 100, valve 102, compressors 103, line 104, 25 line 20, compressors 21, and line 22 to input well 20 24. I prefer, particularly when polymerizer 44 discharges into stabilizer 29, to cycle the greater part of the gas from separator 35 to the input well or wells.

Turning back now to polymerizer 44, this can be operated under the conditions described in connection with Figure 1 and the hot materials from the polymerization coils can be cooled in heat exchangers 42 and then passed into stabilizer 29 through valve 73. This has the advantages discussed in connection with Figure 1 of using a single column for two purposes and utilizing the hot stream from the polymerizer and the cold stream from the distillate recovery operation to good advantage in eliminating or cutting down the amount of reflux and reboiling necessary in connection with this tower. When this operation is carried out in this fashion, tanks 33, 87 and 94 will, of course, contain the polymer product as well as the distillate product and stabilizer 105, fractionator 106, bubble tower 107 and tanks 96 and 108 together with associated equipment, can be eliminated.

On the other hand, it is sometimes advantageous to keep the polymerization products entirely separate from those of the distillate recovery operation and when this is desired valve 73 can be closed and valve 109 opened, thus sending the products from the polymerization operation to a separate fractionation system. Another possibility is to utilize a separate fractionation system only for such part of the polymer products as it is desired to keep separate and to retain the advantages of single tower operation insofar as the bulk of the polymer products is concerned. This can, of course, be accomplished by the control of valves 73 and 109.

The material, if any, from valve 109 passes through line 110 and is used if so desired to heat reboiler 111 whereupon it enters fractionating column 106 which is operated in such fashion that a portion of the gasoline is taken overhead and a portion is eliminated in the bottoms. Fractionator 106 can be supplied with dephlegmator 112 and reboiling apparatus 113. The overhead

from this fractionator passes into stabilizer 105 through 114 and one of the three alternative valved lines 115. The bottoms from this stabilizer are withdrawn through valve 116 and passed through cooler 117 to polymer storage tank 108 as part of the stabilized polymer gasoline product. The overhead from this stabilizer passes through line 118 and partial condenser 119 to separator 120. A portion of the liquid phase from this separator may be passed by pump 121 through valve line 122 to serve as reflux in stabilizer 105 and the remainder is recycled through valve 123, line 124, line 41, heat exchangers 42, and line 43 to the coils of polymerization furnace 44 to produce higher ultimate yields of polymer gasoline. The gas phase from separator 120, on the other hand, may be handled in any one or more of the three alternative ways discussed in connection with the gas phase from separator 35. Thus it may be passed through valve 125, compressors 126, valve 127, line 49, etc., to the coils of polymerizer 44; or through valve 128 and line 129 to burner 54 or to gas storage tank 55; and/or it may be passed through valve 125, compressors 126, valve 130, compressors 103, line 104, line 20, compressors 21, and line 22 to one or more input wells 24. This latter is the preferred operation since it is highly desirable to keep up the amount of gas available for recycling to the formation and this gas, being rich in hydrogen, is a particularly desirable material for recycling. In many instances it will be possible to eliminate part of the compressors referred to since it will not be desired to utilize all of the possible alternative arrangements shown.

Reverting now to the bottoms from fractionating column 106, these can be used if desired to cool the bottoms from bubble tower 107 by closing valve 131 and opening valves 132, thus passing this hot stream through heat exchanger 133 and thence through line 134 into the bubble tower. This bubble tower is conventionally equipped with dephlegmating means 135 and reboiling means 136. It is so operated as to eliminate a heavier than gasoline bottoms and a gasoline overhead. The latter is passed through condenser 137 and line 138 to polymer product tank 108, while the bottoms pass through heat exchanger 133 and cooler 139 to heavy polymer tank 96.

The polymer product of gasoline boiling range can be withdrawn from tank 108 through valved line 140 for storage, further treatment or use or can be and preferably is withdrawn through valve 141 and line 142 for admixture with the distillate gasoline in line 91.

Similarly the heavy polymer can be withdrawn from tank 96 for any desired purpose through valved line 143 and the heavy distillate from tank 94 can similarly be withdrawn through valved line 144. However, it is advantageous to use one or both of these materials as an absorber oil and to operate vessel 19 as a high pressure absorber rather than merely as a retrograde condensation separator since recovery of distillate can, ordinarily be increased quite substantially by so doing.

As has been mentioned previously, the preferred absorber oil is the heavy polymer and this is one of the principal reasons for using a separate fractioning system on at least a part of the polymer products. In connection with small installations it will be apparent that this fractionating system can be considerably simplified. In the preferred operation using heavy polymer as

absorber oil, the heavy distillate is withdrawn through valved line 144, valve 145 being closed, while such part of the heavy polymer as is needed for absorption oil passes through valve 146, pump 147, line 148 and one or both of valves 61 and 62 into the absorber 19.

Vessel 19 when operated as an absorber can usually be operated at a somewhat higher pressure and, if desired, at a slightly higher temperature than when operated as a retrograde condensation separator. Thus as an absorber its pressure may range from 1,000 to 4,000 pounds per square inch, usually from 1,200 to 3,000 pounds per square inch, for instance 2,000 pounds per square inch. The absorber oil in any desired ratio, for instance two to six gallons per thousand cubic feet of gas, can be introduced above baffles 150 or part of it or even all of it can be passed through cooler 17 into the absorber along with the well fluids. The absorber oil, of course, is removed from vessel 19 along with the distillate hydrocarbons and finds its way through surge drum 67 and stabilizer 29 to intermediate storage tank 33 and ultimately to heavy distillate storage tank 94. By going through this route it becomes contaminated, of course, with the heavy distillate and in the preferred operation newly produced heavy polymer is continuously sent to the absorber as absorption medium since its aromatic character and high critical temperature make it possible to operate absorber 19 at a higher pressure than would otherwise be the case. This reduces the amount of compression necessary for recycling the gas to the underground formation or for cycling it to another underground formation and makes for a great reduction in capital costs as well as operating costs.

Figure 3 shows an alternative type of flow diagram combining high pressure absorption and polymerization.

In this figure the products from producing well 11 may be passed through one of driers 14 and thence through cooler 17 and pressure reduction valve 18, all as described in connection with Figure 1. It will be understood, however, that some of these apparatus elements may be omitted depending on the character of the well fluids and the character of the subsequent operations. Thus, for instance, if the well fluids are available at 50 moderate pressure, for instance 1,500 or 2,000 pounds per square inch, pressure reduction will not ordinarily be needed and is not desirable. If the product is very low in water content or if the absorber is operated at a temperature above that at which hydrates form under the particular pressure conditions involved, the drying step can likewise be omitted. However this may be, the well fluids enter a high pressure absorber 19 which may be operated under the temperature and pressure conditions referred to in connection with vessel 19 of Figure 2 when the vessel is operated as a high pressure absorber. As in the case of Figure 1, gases from the top of absorber 19 pass through line 20, compressors 21 and line 22 into one or more input wells 24. The distillate along with the absorber oil, the introduction of which will be described hereinafter, passes out of absorber 19 through valve 25 which is under the control of float 26 and thence passes through line 27 and pressure reduction valve 151 to gas separator 152. The gases flashed off in this separator pass through line 153, valve 154 and one of compressors 155 and thence through heat exchangers 156, 42a and 42b into the coils of polymerizer 44. A portion of these gases may

also be used as fuel passing through valves 157 and 53 to burner 54 with fuel gas tank 55 floating on the line.

The question of which gases will be used for fuel, which for charge to the polymerization furnace and which for reintroduction into a sub-surface reservoir depends on a number of factors. It is important to use gas available at as high a pressure as possible for reintroduction into the formation since this effects a saving on the very important item of compression costs. On the other hand, it is desirable to send gases rich in polymerizable constituents, including C₂ and particularly C₃ and C₄ hydrocarbons, to the polymerization step to improve the ultimate yield of motor fuel. Ideally the gas used as fuel should be low pressure gas poor in polymerizable constituents, i. e. methane and hydrogen, but it is not possible to make a perfect balance between these various factors particularly since the gases available at the highest pressures are usually those which are poorest in polymerizable constituents.

Liquids from separator 152 are removed from the bottom thereof through valve 158 under the control of float 159 and passed through line 160 to a second gas separator 161, thus giving a stage flashing operation. For example, absorber 19 can be operated at 2,000 pounds per square inch, gas separator 152 at 1,000 pounds per square inch and the second gas separator 161 at 500 pounds per square inch. Gases from this second separator pass out through valve 162, lines 163 and 164 and compressors 155 through heat exchangers 156, 42a and 42b into the coils of polymerization furnace 44. Since these gases are richer in polymerizable constituents than those from gas separator 152, it is not desirable to use any of the gases from the second separator as fuel. The liquid phase from this second separator passes out through valve 165 under the control of float 166 to surge drum 167 from which gases may be taken off through valve 168 and line 169 and passed along with those from separator 161 through lines 163 and 164, compressor 155, etc., to polymerizer 44.

The liquid from this surge drum is drawn off through pressure reduction valve 170 and may be used to cool the bottoms from stripper 171 by closing valve 172 and opening valves 173, thus sending the cool stream through heat exchanger 174 and increasing its temperature prior to entry into stripper 171. It will be apparent, as in the case of other heat exchangers previously described, that if so desired a portion of the stream can be passed through the heat exchanger and the remainder passed directly to the column.

In stripper 171 the gasoline and lighter constituents are taken overhead while the heavier than gasoline constituents can be removed through valve 175 (valves 176 and 177 being closed) and thence through heat exchanger 174, pump 178, heat exchangers 156, cooler 179, line 180 and valves 181 to absorbers 19 and 182. Part of this heavier than gasoline fraction must be removed through valved line 183 if valves 176 and 177 are closed.

Returning now to polymerizer 44, the initial polymerization products pass out through transfer line 56, heat exchangers 42b and 42a, line 184, heat exchanger 185, which serves as a reboiler for stripper 171 and thence through line 186 and optionally through heat exchanger 187 under the control of valves 188 into absorber 182. This absorber normally operates at a pressure sub-

stantially under that in absorber 19. The gas from absorber 182 passes out through valve 189 and compressors 103 into line 20 from which it is sent to one or more sub-surface formations.

5 Also the gas from the top of absorber 182 may be used as fuel, being introduced by means of valve 190 and line 191. Liquid is withdrawn from the bottom of absorber 182 through valve 192 which is under the control of float 193. It may then pass through valve 194 and its pressure may be boosted by means of pump 195, thus making it possible to introduce it into gas separator 152 which normally operates at a somewhat higher pressure than absorber 182. For 10 instance, this absorber may operate at 800 pounds per square inch and gas separator 152 at 1,000 pounds per square inch as previously mentioned. On the other hand, absorber 182 may be operated at a considerably higher pressure, for 15 instance 1,000 or 1,500 pounds per square inch and pump 195 can therefore sometimes be omitted. Alternatively, therefore, these liquids can be introduced by means of valve 196, line 197, valved line 198 and line 160 into gas separator 161 or through valved line 199 into surge drum 167 depending on the pressures involved.

20 Whatever route is chosen, at least the higher boiling fraction of the polymerization products together with the absorber oil from absorber 182 join the distillate and absorber oil from absorber 19 in surge drum 167 and pass with it into stripper 171 as previously described.

25 The overhead from stripper 171 passes through partial condenser 200 to separator 201 from which gases can be taken off through valve 202, line 203, line 163, compressors 155, etc., for introduction into the polymerizer. The liquids from this separator are withdrawn by means of pump 204 and a portion of them is returned to 30 the top of the stripper through valve 205 and line 206 to serve as reflux. The remainder passes through valve 207 and line 208 and thence in whole or part, if so desired, through heat exchanger 209 under the control of valves 210 and then through line 211 and one or both of valved lines 212 into stabilizer 105 which is equipped with reboiler 111. In this stabilizer the combined distillate and polymerization products are reduced to the desired flash point and the motor 35 fuel product is withdrawn through valve 116, heat exchanger 209 and cooler 117 to storage tank 213.

40 Gases from stripper 105, rich in butanes, are taken off through line 118 and partial condenser 119 to separator 120, the liquid phase being sent 45 in part through pump 121 and valve 122 to the top of the stabilizer as reflux and in part through valve 123 and line 124. This latter part joins in line 124 with the gaseous phase from the top of separator 120 which is withdrawn through valve 125 by compressors 126 and then passed through 50 a coil 214 in absorber 182 in order to cool the latter and heat the material going to the polymerization coil. This material then passes through heat exchangers 187 and 42b into the 55 coils of polymerizer 44 from which its course is that previously described.

Reverting to stripper 171, I have described sending the entire heavier than gasoline fraction through valve 175, heat exchanger 174, pump 178, etc., for use as absorber oil and, in part, for discharge from the system. However, it is often desirable to use instead of the entire heavier than gasoline fraction, a particular cut from the heavier than gasoline fraction. This 75 can be done by closing valve 175 and opening

valves 176 and 177. The heavier than gasoline fraction then passes through valve 176 and line 215 into fractionator 216 equipped with dephlegmating coil 217 and reboiler 218. This fractionator can be used to produce various cuts such as an overhead cut withdrawn through valve 219 and/or valve 220, side stream cuts withdrawn through any one or more of valves 221 and a bottom cut withdrawn through valve 222 and/or valve 223. Any of these four cuts can be discarded from the system through header 224 and any one of them or any combination of them can be used as absorber oil via header 225 and/or line 226, valve 177, heat exchanger 174, pump 178, heat exchangers 156, cooler 179, line 180 and valves 181 leading to absorbers 19 and 182.

Similarly, of course, fractionation of the material to be used as absorber oil could be applied to the flow diagram of Figure 2 in which the polymerization products and distillate products are kept separate. Thus, for instance, the polymerizer bottoms or heavy polymer in tank 96 of Figure 2 could be fractionated as described in connection with Figure 3 and the desired fraction could be sent to absorber 19.

It will be understood, of course, that the various flow diagrams presented are merely illustrative of some of the possibilities and that other alternatives will occur to those skilled in the art in the light of this description and that my

invention is not restricted to the details shown. On the other hand, it will also be understood that these flow diagrams are simplified for purposes of convenience and that various items of 5 pumping and compressing equipment, insulation, control devices, safety equipment and various other details are not indicated.

Having described my invention what I desire to claim is:

- 10 A method of recovering distillate hydrocarbons from high pressure well fluids and for the manufacture of additional amounts of motor fuel hydrocarbons from said well fluids which comprises fractionating said well fluids at an elevated pressure and a low temperature into a predominantly gas fraction and a liquid fraction containing substantial amounts of both normally gaseous hydrocarbons and gasoline range hydrocarbons, introducing said liquid fraction into a vertically elongated fractional distillation zone at a high level therein, removing from said fractional distillation zone at least one fraction rich in gasoline range hydrocarbons and at least one fraction rich in polymerizable normally gaseous hydrocarbons, subjecting at least a major amount of said last-mentioned fraction to a high temperature at an elevated pressure to cause thermal polymerization, and passing at least a major amount of the hot polymerization products into said fractional distillation zone at a low level therein.
